UNITED STATES PATENT OFFICE.

ISAAC DE FORD, OF FOREST CITY, MISSOURI.

WRENCH.

SPECIFICATION forming part of Letters Patent No. 713,407, dated November 11, 1902.

Application filed June 2, 1902. Serial No. 110,002. (No model.)

To all whom it may concern:

Be it known that I, ISAAC DE FORD, a citizen of the United States, residing at Forest City, in the county of Holt and State of Missouri, have invented a new and useful Vise-Wrench, of which the following is a specification.

My invention relates to wrenches; and the object of the same is to design an adjustable wrench which will be simple in construction and efficient in operation.

The novel construction employed by me in carrying out my invention is fully described in this specification and claimed, and illustrated in the accompanying drawings, forming a part thereof, in which—

Figure 1 is a side elevation of my wrench. Fig. 2 is a longitudinal section of the same.

Like numerals of reference designate like parts in the different views of the drawings.

The numeral 1 designates the body of my wrench, which has a jaw 2 formed integral therewith, which I shall term the "outer stationary" jaw, which jaw extends at right angles to the body, which is uniform in cross-section. Mounted in contact with the front of the body 1 is a sliding bar 3, having an enlarged head 4 on one end, which head is serrated to form a gripping-jaw 5, located to operate with the jaw 2 to grip a nut. A clip 6 is secured to the bar 3 and embraces the body 1, and thereby serves as a guide. A clip 7 is connected to the lower end of the body 1 and embraces the lower end of the bar 3 to serve as a guide and also as a hand-grip in operating the tool. The end of the sliding bar 3 is reduced and threaded to form a screw 8, which is engaged by an internally-threaded cylinder 9, connected by a neck 10 to a knurled adjusting-nut 11. The cylinder 9 fits snugly in notches 12 and 13, formed in the

body 1 and clip 7, while the neck 10 is engaged by the clip 7. By this arrangement the nut 11 is held against all longitudinal movement. A transverse aperture 11^a is formed in the nut to enable it to be turned by a key.

To adjust my wrench for nuts of different sizes, the nut 10 is turned by the fingers or by a key. The location of the nut renders the turning of it very easy, since it extends beyond the end of the wrench and may be revolved continuously with a key without the necessity of letting go to take a new hold, as is always necessary when the nut is located within an aperture or parallel to another member.

I do not wish to be limited as to details of construction, as these may be modified in many particulars without departing from the spirit of my invention.

Having described my invention, what I claim as new, and wish to secure by Letters Patent, is—

In a wrench, the combination of a body having a jaw on one end, a slidingly-mounted bar bearing a jaw on one end located to coöperate with said first-mentioned jaw, the other end of said bar being reduced to form an adjusting-screw, a clip connected to said sliding bar and embracing said body, a clip connected to said body and embracing said sliding bar, and an adjusting-nut having a cylindrical portion connected thereto by a neck, said cylindrical portion fitting in a notch in said clip with said nut projecting beyond the end of the said body, substantially as described.

ISAAC DE FORD.
